CABLE SUPPORT PACKAGE

Albert B. Chance, Centralia, Mo.

Application June 1, 1932, Serial No. 614,722

3 Claims. (Cl. 206—46)

The present invention relates to cable supports, and is particularly concerned with improved methods of packing cable supports or loops of the type utilized for supporting a conductor cable 5 from a steel cable carried by the poles or other supporting members.

It has been customary to pack cable supporting loops or rings of the type illustrated in this application in sacks, usually placing five hundred 10 to a thousand in a sack. These cable loops or rings have such a tendency toward entanglement that the lineman hanging the cable loses a great deal of time in untangling the cable loops from each other. Sometimes more time is required 15 to untangle the cable loops than would be required to place them in position to support the cable.

One method of reducing the entanglement and saving some of the time required for untangling, 20 is to pack the cable loops in smaller sacks, but this does not prevent entanglement, and a very small number of the cable loops, if assembled together at random in a sack, will become so entangled that a great deal of trouble is encountered 25 in untangling the loops.

One of the objects of the present invention is the elimination of the entanglement of the cable loops or rings which is occasioned by the methods of packing utilized in the prior art.

Another object of the invention is the provision of an improved method of packing cable rings or loops of the class described, by means 30 of which the entanglement of the respective loops is eliminated and the loops are systematically arranged so that they can be removed from the package and assembled with the cable with a minimum amount of effort and at a considerable saving of time.

Another object of the invention is the provision of an improved package consisting of a plurality of cable loops of the class described, having improved characteristics from the point 40 of view of avoiding entanglement of the loops, and also to facilitate the assembly of the loops with the cable by means of routine motions of the workmen, thereby saving a great deal of time in this work.

Other objects and advantages of the invention will be apparent from the following description, 50 and from the accompanying drawing, in which similar characters of reference indicate similar parts throughout the several views.

Referring to the single sheet of drawings,

Fig. 1 is an elevational view of the conductor cable, such as that utilized for a telephone sys-

tem, supported by one of the cable supporting loops and a steel cable;

Fig. 2 is an enlarged view of the steel cable and cable supporting loop, viewed from a different angle, the point of view being located at the 5 right side of Fig. 1;

Fig. 3 is a side elevational view of a cable loop packing constructed according to the present invention; and

Fig. 4 is a top plan view of the same packing. 10

In order to understand the difficulties involved in the packing of cable loops of this type, the characteristics of the cable loop itself will first be described in detail.

Referring to Figs. 1 and 2, 10 indicates the usual 15 steel cable which is carried by the telephone poles to provide a support by means of the cable supporting loops 11 for the conductor cable 12, which usually consists of a lead covered cable, including a multiplicity of insulated wires. 20

The steel cable 10 is placed under a predetermined degree of tension and is secured to the telephone poles in a manner well known in the art, and the lead cable 12 is supported at a multiplicity of points between the poles from the 25 steel cable 10 by means of the supporting loops 11. The spacing of the cable supporting loops 11 for any particular job will depend upon the characteristics of the cables employed, such as weight, strength, etc. 30

The cable supporting loops which have been selected for the purpose of illustration of the present packing are of the type which are adapted to be firmly secured upon the steel cable 10 by virtue of their peculiar formation and cooperation 35 with the steel cable 10. Sometimes these cable supporting loops vary in size, and in the distance of their supporting surface from the steel cable 10, so that isolated cable loops may not even be engaged by the lead cable 12. Such isolated loops, 40 supporting no weight, might become disconnected, were it not for the fact that the present cable supporting loops are so constructed that they are firmly secured to the steel cable 10, whether or not they carry weight. They do not depend upon 45 the weight of the lead cable to secure them in place.

The loops or rings are preferably formed of flat steel wire, which is preferably galvanized after the lengths of cable are cut and after the finished 50 loop has been shaped to the form shown in Figs. 1 and 2. Each loop is preferably provided with a substantially cylindrically curved supporting surface 13 of a size large enough to receive the lead cable 12, and as a general rule the loop which 55

comprises the curved portion 13 is considerably larger than the cable 12.

The curved portion 14 is so arranged that it will extend about the cable 12, as shown in Fig. 1, 5 and the legs of the curved portion 14 extend diagonally upward to the left and right, as shown at 14 and 15 in Fig. 1; that is, the legs 14 and 15 project diagonally from the plane of the curved portion 13, in order to extend toward two different parts of the steel cable 10. The legs 14 and 10 15 also bend over toward each other, as shown in the end view in Fig. 2, since both of the ends of the loop must be brought into the approximate plane of the steel cable 10 to which they are to be 15 attached.

At the point 16 the leg 15 is curved substantially horizontally, being provided with a flat horizontal portion 17 which is located below the steel cable 10. The leg 15 turns upward at substantially a 20 right angle at the point 18 and extends upward about the steel cable 10, being formed with a curved portion 19 and a downwardly extending end 20. The end 20 is spaced from the flat portion 17 a distance which enables the steel cable 25 10 to pass through the space 21.

The leg 14 has an upward curvature at the point 22 extending upward to a hump 23 which is above the lower edge of the steel cable 10 when the device is assembled as in Fig. 1. The hump 23 30 is the location of a downwardly bent portion 24 which is formed with a depression 25 on its upper side for receiving the steel cable 10. From the point of the depression 25 the flat wire of this end of the loop curves upward helically about the 35 steel cable 10, being provided with substantially a full turn of a helix when viewed from the left end of Fig. 1, but the end 26 terminates at a point spaced from the body of the helical turn 27. In other words, the space 28 between the end 26 and 40 the body of the flat wire is wide enough to permit the insertion of the steel cable 10 into the loop formed by this helical turn 27.

The curved supporting surface 25 below the hump 23 is located at such a point that the cable 45 supporting loop must be placed under some tension when it is assembled with the two cables, as shown in Fig. 1. Thus the loop 11 tends to deform the steel cable 10 from its straight line position, as shown in Fig. 1, and the downward pressure on the curved surface 25 by the steel 50 cable 10 tends to draw the other curved end 19 of the cable loop or ring 11 into engagement with the steel cable 10.

The two ends 19 and 27 of the loop engage the 55 top of the steel cable 10, and the curved part 25 of the loop engages below the steel cable 10. The hump 23 is located on the side of the steel cable 10 opposite from the end 26 so that the cable supporting loop is very firmly secured to the steel cable 10 when it is properly assembled therewith.

It will thus be observed that there is an opening 29 between the two ends 20 and 26 of the cable supporting loop, the opening 29 being such 60 that the lead cable 12 may pass through it in order to effect an assembly of the parts without the necessity for passing the rings or loops over the ends of the lead cable 12.

This opening 29 in the cable supporting loops or 70 rings is the cause of much of the entanglement which results when these cable rings are placed in sacks.

Another cause of this entanglement is the hook shaped formations 19-20 and 26-27 at the ends 75 of these flat wire members, as these hooked for-

mations tend to become entangled with other parts of adjacent loops in the sacks.

Suffice it to say that the difficulty of separating these cable supporting rings or loops can hardly be appreciated except by trying to separate a 5 sack full of these loops. It is impossible to pick up even one of the cable rings without lifting the whole entangled mass of them, and in separating one ring from the rings with which it may then be entangled the irregularity of formation of the 10 rings is such that they are apt to be moved into greater entanglement with other adjacent rings or loops.

A great deal of time is spent by linemen trying to untangle these loops, once they become entangled, as they do when they are placed in sacks. 15

One of the most important features of the invention is the prevention of the entanglement of these cable supporting rings at any time during their handling. 20

Referring to Figs. 3 and 4, these are views of one of the preferred forms of packaging or modes of packing cable supporting rings or loops which I have found are capable of preventing the entanglements of the rings or loops. The method of 25 preventing entanglement will now be described in detail.

In order to avoid the loss of time incident to the untangling of the entangled loops, I prefer to handle the loops during the process of their 30 manufacture so that they never become entangled. As the loops are inspected after they have been manufactured, they are preferably nested in multiples, the number of loops placed in a package being appropriate to give satisfactory pack- 35 ing for the particular size of loop. The present loops require particular attention in the nesting of the loops on account of their peculiar formation, and it will be observed that they are arranged with their lower curved portions 13 side 40 by side with each other. This places the hooked formations 19 side by side adjacent hooked formations of adjacent loops, but the helical forma- 45 tions 27 at the opposite end do not nest so easily and would not be nested if they were merely placed side by side with each other.

Referring to Fig. 3, the helical formations 27 and 27A of the loops 11 and 11A can be nested by merely passing the part 25 of the loop 27 through the space 28 of the loop 27A. The loop 27A is 50 then twisted slightly with respect to the loop 27 until the two loops arrive at the position shown, and the loops may be nested with their helical ends each curved about the body of the next adjacent loop, as shown in Figs. 3 and 4. 55

One advantage of this mode of nesting is that the helical or curved hooks at the left end of the loops in Figs. 1 and 2 are partially filled by their nesting with the adjacent loops, and it is practically impossible to entangle this end of a package 60 with other packages.

The nested loops are preferably secured together in such a manner that they may be maintained in the position shown in Fig. 3, and also preferably in such a manner that the wide opening 29 between the legs of the loop is closed and so that the hooked formations 19 at the opposite ends of the loops are also filled. 65

One way of accomplishing this result is to pass a strip of material such as cardboard, tape, or 70 the like, about the vertically extending portion 30 of the loops in Fig. 3 and about the vertically extending portions 31 at the other end of the loops in Fig. 3. It is preferred to use a piece of corrugated cardboard on account of the fact that such 75

material possesses sufficient thickness to substantially fill the hooked formations 19. Such material is also sufficiently stiff to be maintained in position upon the vertical portion 30 by the engagement of the lower side 32 of the strip 33 with the shoulders 17.

It will be noted also that the vertically extending portions 30 curve slightly toward the right in Fig. 3, and the hump at the bend 22 also serves to keep the securing strip 33 in place. The securing strip 33 is preferably of the same width as the distance from the portion 17 to the upper end of the hook 19, and after being passed about both ends of the loops the ends of the strip 33 are preferably secured together.

One convenient mode of securing the ends together is by means of stapling, the staple 34 being shown in Figs. 3 and 4. Other convenient modes which might also be utilized are cementing the overlapping ends, taping, sewing, riveting, or any of the conventional modes of fastening cardboard parts together. The staple 34 consists of a substantially U-shaped member, the legs of which are driven through both of the ends of the cardboard strip, and the ends of the staple 34 are bent over on the rear side.

It will be noted that the cardboard strip 33 closes the relatively large opening 29 between the legs of the loop, and it also closes the hooked formations at one end of each of the loops and maintains the curved formations at the other ends in nested relation. The bodies of the loops are maintained in engagement with each other because the cardboard strip draws the right hand loop over into nesting engagement with all of the other loops, which in turn react against the outermost loop at the left hand side which is engaged by the cardboard strip.

When cable supporting loops packaged according to the present invention are utilized, the strip 33 may be broken very easily, and the loops may be taken from the left hand side of the package in Fig. 3 by grasping the loop at that side and turning it backward in a counterclockwise direction in Fig. 3 until the curled end on the left leg of the loop is twisted out of engagement with the rest of the package.

Conductor cables may be assembled with the supporting loops and steel cable very quickly, without any loss of time due to the entanglement of the cable supporting loops, when this package is employed. The packages may also be thrown into sacks or boxes without any entanglement, and the package promises to be of great commercial importance on account of the high cost of labor and the saving of time of labor which is accomplished by means of this method.

It will thus be observed that I have invented an improved method of packing and an improved

package for maintaining the loops in such relation that the entanglement of the loops is effectively prevented.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. A package of cable supporting loops comprising a plurality of said loops, each having a hook-like formation at one end and each having a helical formation at the opposite end, said loops being placed side by side with the hook-like formations adjacent each other and each of the helical formations twisted about the body of an adjacent loop, and a securing member about said cable-supporting loops, said securing member being threaded through said hook-like formations and bridging the ends of said loops to prevent other loops from entering the opening between the ends of said loops.

2. A package of cable supporting loops comprising a plurality of said loops, each having a hook-like formation at one end and each having a helical formation at the opposite end, said loops being placed side by side with the hook-like formations adjacent each other and each of the helical formations twisted about the body of an adjacent loop, and a securing member about said cable-supporting loops, said securing member being threaded through said hook-like formations and bridging the ends of said loops to prevent other loops from entering the opening between the ends of said loops, said securing member comprising a strip of sufficient width to substantially fill said hook-like formations.

3. A package of cable supporting loops comprising a plurality of said loops, each having a hook-like formation at one end and each having a helical formation at the opposite end, said loops being placed side by side with the hook-like formations adjacent each other and each of the helical formations twisted about the body of an adjacent loop, and a securing member about said cable-supporting loops, said securing member being threaded through said hook-like formations and bridging the ends of said loops to prevent other loops from entering the opening between the ends of said loops, said securing member comprising a strip of corrugated paper having its adjacent ends secured together by a metallic member.

ALBERT B. CHANCE.
